INSULATING SUPPORT FOR A SHEATHED ELECTRIC SURFACE HEATER

Donald M. Cunningham, 2507 Greensburg Pike,
Pittsburgh, Pa. 15601

Filed Sept. 21, 1973, Ser. No. 399,379

Term of patent 14 years

Int. Cl. D23—03
U.S. Cl. D23—127

FIG. 1.

FIG. 2.

FIG. 4.

FIG. 3.

FIG. 1 is a perspective view of an insulating support for a sheathed electric surface heater, showing my new design;

FIGS. 2 and 3 are top and bottom plan views, respectively; and

FIG. 4 is a sectional view corresponding to the line 4—4 of FIG. 2.

I claim:

The ornamental design for an insulating support for a sheathed electric surface heater, substantially as shown.
